UNITED STATES PATENT OFFICE

2,522,019

SPARK PLUG SHIELD

Arthur H. Cadman, Bloomfield, N. J., assignor to
 Breeze Corporations, Inc., Newark, N. J., a corporation of New Jersey

Application June 12, 1946, Serial No. 676,317

1 Claim. (Cl. 174—35)

1

This invention relates to shields such as are placed around spark plugs of internal combustion engines, and particularly such as are adapted to prevent the ignition system from interfering with radio communication.

An object of this invention is to provide a spark plug shield which may be applied to any standard spark plug.

Another object of this invention is to provide an easily assembled spark plug shield.

A feature of this invention is the locking cap member which permits of easy inspection and installation.

Another feature of this invention is the metal foil liner which insures the metal-to-metal contact between the shield shell and the cap.

An object of this invention is to provide a shield to be used on motors where the spark plug is held within a recess in the engine block.

A further object of this invention is to provide an extremely light and inexpensive radio shield for a spark plug.

The invention consists of the construction, combination and arrangement of parts, as hereinafter illustrated, described and claimed.

In the accompanying drawings, forming part hereof, is illustrated one form of embodiment of the invention, in which drawings similar reference characters designate corresponding parts, and in which:

Figure 1 is a side elevation of a complete embodiment of the invention, with the cap member cut away to show the construction thereof and certain hidden portions shown by dotted lines.

Figure 2 is a longitudinal section of the cap member.

Figure 3 is a bottom plan of the cap member, partly broken away.

Referring to the drawings, and particularly to Figure 1, 10 represents a metallic shell somewhat cup-like in shape. The lower portion of the shell is flared inwardly at 11 to meet the base 12 thereof. A hole 13 is provided in said base 12 for the admission therethrough of the lower portion of a spark plug 14. A reinforced rim member 15 is secured to the upper edge of the shell 10 by silver solder at 16. The rim member 15 is provided with a rim bead 17 for the purpose of receiving a cap member 18 and holding said cap member to the shell 10.

The cap member 18, as best shown in Figure 2, is provided, along its rim, with a plurality of peripheral detents 19. The detents 19 have their extending ends 20 turned back upon themselves to receive a locking wire 21. The wire 21 is passed

2

through said detents 19 and is engaged by a locking lever 22 formed of another piece of wire.

The operation of the locking device is well known. When the wire 22 is pressed downwardly, the locking wire 21 is drawn more tightly around the cap member 18, thereby securing it to the rim member 15. A gasket 24 is inserted in the upper portion of the cap member 18 and may be of rubber or any similar insulating material. A layer 10 of metal foil 23 is disposed upon the upper surface of the gasket 24 in such manner that the extending edges 25 of said foil 23 may be brought over the periphery of the gasket 24 so as to lie upon the lower face of said gasket in a circular ring, as shown in Figure 3.

When the cap member 18 is applied to the reinforced rim 15 of the spark plug shield, and the locking lever 22 pressed downward, the foil edge 25 of the foil liner 23 provides a metal-to-metal contact between the shield shell 10 and the cap member 18.

The shell member 10 is provided with an opening 26 spaced from the upper edge of the shell 10, for the purpose of admitting the contact 27 of the ignition cable 28. An externally threaded outlet shield 29 is carried by the shell body 10, adjacent this opening 26.

In applying this shield to the motor, the spark plug 14 is first removed from the engine block and then inserted in the opening 13 in the spark plug shield shell 10. The spark plug 14 is then threaded back into the engine block until the base 12 of the spark plug shield is tightly held between the hexagonal member 30 on the spark plug 14 and the block surface. This assembly grounds the shield to the engine block. The ignition wire contact 27 on the cable 28 is then pulled through the outlet 29 into the shell chamber and contact made between the spark plug 14 and the ignition cable.

The coupling nut 31 located on the ignition shielding conduit 32 is tightened on the external threads of the outlet shield 29. When the electrical connection is made, the cap member 18 may be pressed downward over the reinforced rim member 15 of the shell 10 and the locking wire 21 drawn tight by forcing the locking lever 22 downwardly.

The edges 25 of the foil liner 23, best shown in Figure 3, complete the electrical contact of the spark plug shield. Breather holes 33 are provided in the inwardly flared portion of the shell 10, and also along the central portion of the rim section 15. These holes 33 prevent the collection of moisture within the spark plug shield.

The simplicity of the operation and construction of this spark plug shield become apparent from the foregoing description.

It is adaptable for all types of engines, and the inwardly flared portion of the shell body makes it possible to use this shield on engines where the spark plug is retained in a well or recess in the cylinder block.

Having thus fully described the invention, what is claimed as new and desired to be secured by 10 Letters Patent of the United States, is:

In a spark plug shield, an electrically conductive shell comprising a cylindrical member inwardly flared at its base and provided with an inturned flange at the bottom thereof adapted to 15 fit snugly around the base of a spark plug, a wire spring retained cap member secured thereon comprising a plurality of detents integral with said cap and having their ends turned back upon themselves to receive the said wire and a lever 20 adapted to draw the said detents together by means of the wire, said cap supporting, upon the inside surface thereof, a resilient gasket having

a layer of metal foil disposed upon the upper surface thereof and continued over the edges of the said gasket to form a peripheral strip upon the lower surface thereof and a shielding outlet carried by the wall of the said shell to admit an ignition cable into the shield.

ARTHUR H. CADMAN.
